UNITED STATES PATENT OFFICE.

CUTLER D. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY.

SOLE-PRESSING MACHINE.

Application filed June 26, 1919. Serial No. 306,991.

To all whom it may concern:

Be it known that I, CUTLER D. KNOWLTON, a citizen of the United States, residing at Rockport, in the county of Essex and 5 State of Massachusetts, have invented certain new and useful Improvements in Sole-Pressing Machines; and I do hereby declare the following to be a full, clear, and exact 10 description of the invention, such as will enable others skilled in the art to which it applies to make and use the same.

The present invention relates to sole pressing machines, and more particularly to the 15 type of sole pressing machines which are known in the art as sole laying machines.

In sole laying machines as now commonly 20 constructed a relative movement of approach is imparted to the jack and sole pressing pad to bring the sole in contact with the shoe by means of a treadle actuated mechanism, and thereafter a relative sole pressing movement is imparted to the jack and sole pressing pad by power actuated mechanism thrown into operation by the operator. The treadle 25 operated mechanism of these machines puts considerable work on the operator and also renders the machine somewhat slow in operation.

An object of the present invention is to 30 produce a sole laying machine which shall be simple in construction and efficient in operation, and in which the operator will be relieved of the work of imparting the relative movement of approach to the shoe supporting jack and sole pressing pad.

With this object in view a feature of the 35 present invention contemplates the provision in a sole laying machine of the improved power operated mechanism hereinafter described and claimed for imparting to the jack and pad both relative movements of approach and sole pressing movements.

Other features of the invention consist 40 in certain constructions, arrangements and combinations of parts hereinafter described and claimed, the advantages of which will be obvious to those skilled in the art.

The invention will be readily understood 45 from the following description and accompanying drawings, in which:

Figure 1 is a front elevation of a machine embodying the features of the invention in 50 their preferred form; Fig. 2 is a left end elevation of the machine; Fig. 3 is a detailed 55 vertical sectional view, partly in elevation,

of a controlling valve mechanism; Fig. 4 is a vertical sectional view, partly in elevation, taken on the line 4—4 of Fig. 2; and Fig. 5 is a horizontal sectional view, partly in elevation, taken on the line 5—5 of Fig. 2. 60

The present invention is illustrated in the drawings as embodied in a machine comprising twin presses to lay the soles on right and left shoes respectively, constructed and arranged so that the sole of one shoe is laid 65 by one press while the work is being changed on the other press.

Each of the twin presses comprises a shoe supporting jack 2 which is rigidly secured to the upper ends of a pair of vertical support rods 4 projecting from the upper ends of side standards 6. The lasted shoe is held by the supporting jack and the sole is laid by a sole pressing pad 8 mounted in a pad carrier 10 which is suitably secured to a cross 70 piece 12 slidably mounted on the vertical rods 4. The parts above described are substantially the same as the corresponding parts of the sole laying machine illustrated and described in the patent to Davenport, 75 No. 1,066,473, dated July 8, 1913.

In the machine illustrated in the drawings power actuated mechanism is provided for imparting first a movement of approach to the pad carrier 10 so as to press the sole 80 lightly against the shoe, and then a pressing movement sufficient to properly shape the sole. This mechanism comprises a fluid operated piston and suitable mechanical connections between the piston and the pad 85 carrier which are constructed to act with increasing mechanical advantage during a uniform movement of the piston to impart first a relatively fast movement of approach to the pad, and then a relatively slow pressing movement. By providing connections 90 between the piston and the pad carrier operating in this manner an excessive pressure for operating the piston is rendered unnecessary and a comparatively rapid motion of 95 the piston is permitted without undue expenditure of the fluid used in its operation, and without producing any objectionable shock or jar when the pad is brought into 100 pressing position. Also a smooth running, 105 quick acting machine is produced in which the pressing pad is quickly brought into pressing position, and is then slowly and powerfully moved to exert the requisite 110 pressure on the sole. The connections be-

tween the piston and pad carrier have provision for adjustment to vary the mechanical advantage thereof and thereby vary the amount of pressure applied on the work. 5 These connections comprise a carrier 14 which in turn comprises a shaft 16 having reduced end portions journaled in the upper ends of a vertically reciprocating yoke 18 by means of which the carrier is actuated. 10 The shaft 16 is guided by means of guide rolls or trunnions 20 carried by the outer ends thereof, which engage the vertical walls of slots 21 in the standards 6. During the vertical reciprocation of the shaft 16, a reciprocating rotary movement through substantially 180 degrees is imparted thereto by means of gears 22—22 which are secured to the shaft adjacent the inner ends of the bearings in the yoke 18, which gears operatively engage racks 24 secured to a web 26 connecting the standards 6. The sole pressing pad is connected to the shaft 16 by means of a link or connecting rod 30 having one end pivotally connected to ears 32 15 projecting downwardly from the under side of the pad carrier 10 and its other end pivoted on a wrist pin 34 mounted in the outer end of a block 36. The block 36 is mounted in a recess 38 in the shaft 16 and in effect 20 constitutes a crank arm. When the shaft 16 is at the limit of its down stroke, the wrist pin 34 is positioned so that its axis is to one side of the axis of the shaft 16 and in the same horizontal plane (Fig. 4) and during 25 the up stroke of the shaft 16 the wrist pin is moved substantially 180 degrees about the axis of the shaft. It will be noted that with this construction, as the wrist pin approaches the dead center position of the connecting rod 30 and the block or crank arm 36, an initially rapid movement which decreases in velocity will be imparted to the sole pressing pad to position the pad in proximity to the sole of the shoe supported 30 by the jack and during the remainder of the movement of the wrist pin a comparatively slow but relatively powerful pressing movement will be applied to the sole through the pad. 35

In order to vary the pressure applied on the sole as desired, the block 36 is mounted to slide in the recess 38 and is adapted to be adjusted to move the wrist pin 34 toward and from the axis of the shaft by means of 40 a nut 40 threaded on a stud 42 projecting from the inner end of the block 36, the nut being held from longitudinal movement by engagement with the end walls of an aperture in a lug 44 projecting from the shaft 16. The block 36 is held in adjusted position by means of a spring pressed plunger 46 mounted in the lug 44 which is adapted to engage a series of notches 48 provided in the periphery of the nut. 45

The fluid operated mechanism hereinbe-

fore referred to, for yieldingly actuating the carrier 14, comprises a piston 50 having a piston rod 52 secured thereto, which at its upper end carries the yoke 18. The piston 50 is mounted in a cylinder 54 having a port 56 at its lower end. The admission and discharge of compressed air or other fluid from the cylinder of both presses is controlled by a slide valve mechanism 58, the valve chamber of which is connected to the cylinders by pipes 60 which lead from the ports in the cylinders to ports 62 in the valve casing 64. 70

Compressed air is admitted into the valve chamber through a port 66 located in the casing 64 between the ports 62, which port 66 is connected to a source of compressed air supply. The valve is connected by a link 68 to an actuating lever 70 centrally pivoted at 72. Foot treadles are formed at the ends of the lever 70 which are conveniently located in front of the respective presses. 80

The construction of the valve mechanism 58 is such that upon depression of one of the treadles, compressed air is admitted into the cylinder of its adjacent press, which through the piston raises the sole pressing pad as previously described. It is desirable, when one of the treadles is depressed, that it shall remain depressed to cause the pad of the adjacent press to continue to apply pressure to the sole until the work has been changed on the other press, and the latter press is operated. To this end means are provided for holding either of the treadles depressed until the other treadle is actuated to raise its associated pad. This means comprises an arm 74 centrally located and projecting upwardly from the treadle lever 70. The free end of the arm 74 is provided with notches 76 which are adapted alternately to engage a spring pressed plunger 77 to hold the lever 70 in the position to which it is moved by the depression of either of the treadles the full amount. When the valve mechanism 58 is actuated to open communication between the compressed air inlet port 66 and one of the ports 62, the other port 62 is opened to the atmosphere which permits the air to be expelled from its associated cylinder, whereupon the pad connected with the piston in the cylinder is returned to its retracted position. It will be noted that with this construction, the operator by manipulation of the foot treadles may stop either pad at any point in its travel to permit readjustment of the work. 90

In the operation of the illustrated machine, the amount of pressure applied on a sole is determined by the adjustment of the wrist pin 34 in the carrier 14. As the sole pressing pads rise, the mechanical advantage of the uniform pressure of the fluid against the piston 50 increases until a point is reached where this pressure just balances 100 105 110 115 120 125 130

the pad pressure for which the machine has been set, when the movement of the piston will stop. In some cases, however, it is desirable that the limit of the sole pressing movement shall be positively fixed, or that means be provided to ensure that the wrist pin 34 shall not travel about the axis of the shaft 16 more than 180 degrees. To this end, adjustable means is provided for limiting the up strokes of the pistons 50. This means comprises stops in the form of caps 78 threaded on the upper ends of the cylinders. By screwing the caps up or down the limits of the up strokes of the pistons may be varied as desired.

This device might be used, for example, when the pin 34 was adjusted to be outside the pitch circle of the gears 22, in which case the pressure would diminish at the end of the stroke if the pin 34 were allowed to travel the full 180 degrees around the axis of the shaft 16.

A machine embodying the several features of the present invention in their preferred form having been specifically described, what is claimed is:

1. A sole pressing machine having, in combination, a shoe supporting jack, a sole pressing pad, mechanism acting with increasing leverage to move the jack and pad relatively to apply pressure to the sole of a shoe placed on the jack, and fluid operable means for actuating said mechanism.

2. A sole pressing machine having, in combination, a shoe supporting jack, a sole pressing pad, mechanism for moving the jack and pad relatively to apply pressure to the sole of a shoe placed on the jack, means comprising a crank arm for adjusting said mechanism to vary the amount of pressure applied by the jack and pad, and fluid operable means for actuating said mechanism.

3. A sole pressing machine having, in combination, a shoe supporting jack, a sole pressing pad, mechanism acting with increasing leverage to move the jack and pad relatively to apply pressure to the sole of a shoe placed on the jack, said mechanism having provision for adjustment to vary said leverage, and fluid operable means for actuating said mechanism.

4. A sole pressing machine having, in combination, a shoe supporting jack, a sole pressing pad, mechanism for imparting a relative movement of approach to the jack and pad to position the pad and the sole of a shoe placed on the jack in proximity and then to impart a relative slow pressing movement to the jack and pad to apply pressure to the sole, means under the control of the operator throughout the duration of said movements of the jack and pad for actuating said mechanism, and means for adjusting said mechanism to vary the pressure applied by the jack and pad.

5. A sole pressing machine having, in combination, a shoe supporting jack, a sole pressing pad, mechanism for imparting a relative movement of approach to the jack and pad to position the pad and the sole of a shoe placed on the jack in proximity, and then to impart a relative slow pressing movement to the jack and pad to apply pressure to the sole, means under the control of the operator during said relative pressing movement of the jack and pad for actuating said mechanism, and means for adjusting said mechanism to vary the pressure applied by the jack and pad.

6. A sole pressing machine having, in combination, a shoe supporting jack, a sole pressing pad, mechanism acting with increasing leverage to impart a relative movement of approach to the jack and pad to position the jack and pad in proximity and then to apply relatively a slow pressing movement to the jack and pad to apply pressure to the sole of a shoe placed on the jack, and fluid operable means for actuating said mechanism.

7. A sole pressing machine having, in combination, work engaging members comprising a shoe supporting jack and a sole pressing pad, a bodily movable crank arm, a link connecting the crank arm with one of said work engaging members, means for simultaneously imparting to the crank arm a rotary movement and a movement in a plane perpendicular to its axis to move the jack and pad relatively to apply pressure to the sole of a shoe placed on the jack, and means for adjusting the point of connection of the crank arm and link toward and from the axis of the crank arm.

8. A sole pressing machine having, in combination, work engaging members comprising a shoe supporting jack and a sole pressing pad, and mechanism acting with increasing leverage to move the jack and pad relatively toward each other comprising a carrier having a reciprocating rotary movement and a reciprocating movement in a plane perpendicular to its axis, and a connection between said carrier and one of said work engaging members. said mechanism having provision for adjustment between the carrier and the said one of the work engaging members to vary the mechanical advantage of the mechanism.

9. A sole pressing machine having, in combination, work engaging members comprising a shoe supporting jack and a sole pressing pad, and mechanism acting with increasing leverage to move the jack and pad relatively toward each other comprising a carrier having a reciprocating rotary movement and a reciprocating movement in a plane perpendicular to its axis, and a connection between said carrier and one of said work engaging members, said mechanism

having provision for adjustment to vary said leverage.

10. A sole pressing machine having, in combination, work engaging members comprising a shoe supporting jack and a sole pressing pad, mechanism acting with increasing leverage to move the jack and pad relatively toward each other comprising a carrier having a reciprocating rotary movement and a reciprocating movement in a plane perpendicular to its axis, and a connection between said carrier and one of said work engaging members, and means comprising a fluid actuated piston connected

with the carrier for actuating said mechanism.

11. A sole pressing machine having, in combination, a shoe supporting jack, a sole pressing pad, and mechanism including means operated by fluid under pressure for relatively actuating the jack and pad to apply pressure to the sole of a shoe placed on the jack, said mechanism comprising a crank arm adjustable to vary the amount of pressure applied to the sole without varying the fluid pressure.

CUTLER D. KNOWLTON.
